UNITED STATES PATENT OFFICE

107,682

DESIGN FOR AN AUTOMOTIVE RADIATOR SEALING AND PRESSURE RELIEF VALVE OR THE LIKE

Arthur F. Grigg, Metuchen, and John E. Zeller,
Montclair, N. J.

Application December 4, 1937, Serial No. 73,380

Term of patent 14 years

To all whom it may concern:

Be it known that we, Arthur F. Grigg and John E. Zeller, citizens of the United States and residents, respectively, of Metuchen, in the county of Middlesex and State of New Jersey, and of Montclair, in the county of Essex and State of New Jersey, have invented a new, original, and ornamental Design for an Automotive Radiator Sealing and Pressure Relief Valve or the like, of which the following is a specification. Reference may be had to the accompanying drawing, forming a part of this specification, wherein:

Figure 1 shows a side elevational view of the

automotive radiator sealing and pressure relief valve or the like embodying our design. The other side of the valve is the same as shown in Figure 1.

Figure 2 shows a top plan view of the same in which the dominant features are shown in full lines.

We claim:

The ornamental design for an automotive radiator sealing and pressure relief valve or the like substantially as shown and described.

ARTHUR F. GRIGG.
JOHN E. ZELLER.
